(57) **CLAIM**

The ornamental design for the dressing chair for the handicapped and infirmed.

DESCRIPTION

FIG. 1 is an isometric view of the dressing chair for the handicapped and infirmed;
FIG. 2 is a left side view, the right side being a mirror image thereof;
FIG. 3 is a front view thereof;
FIG. 4 is a rear view thereof, with the elevated rack removed;
FIG. 5 is a top plan view of FIG. 4;
FIG. 6 is a bottom view thereof;
FIG. 7 is an isometric view of the dressing chair for the handicapped and infirmed and including a tray connected to its right side; and,
FIG. 8 is a modified dressing chair for the handicapped and infirmed, configured to mount directly to the floor.
